United States Patent Office.

DAVID W. DOWNS AND FRANKLIN P. RAND, OF NORTH PROVIDENCE, RHODE ISLAND.

Design No. 3,570, dated July 6, 1869.

DESIGN FOR A CAST-IRON SETTEE.

The Schedule referred to in these Letters Patent and making part of the same.

Claim.

What we claim as our invention, and desire to secure by Letters Patent, is—

The design for iron settee, herein shown.

Witnesses: DAVID W. DOWNS.
ROYAL LEE, FRANKLIN P. RAND.
GEO. A. CARPENTER.

To all whom it may concern:

Be it known that we, DAVID W. DOWNS and FRANKLIN P. RAND, of North Providence, in the county of Providence, and State of Rhode Island, have originated a new Design for Iron Settee, of which the accompanying is a full, clear, and exact drawing.
